UNITED STATES PATENT OFFICE.

RALPH HOLLAND AND JOHN A. WIRT, OF LARAMIE, WYOMING.

APPARATUS FOR CLARIFICATION OF GASOLINE.

Application filed February 23, 1924. Serial No. 694,608.

To all whom it may concern:

Be it known that we, RALPH HOLLAND and JOHN A. WIRT, citizens of the United States, residing at Laramie, in the county of Albany 5 and State of Wyoming, invented a new and useful Apparatus for Clarification of Gasoline, of which the following is a specification.

The object of our invention is to provide 10 an improved apparatus and novel method for cleaning clothes or fabrics and for thereafter clarifying the cleaning solution and making it possible to use this solution repeatedly thereby reducing the cost of the 15 cleaning; and to provide means whereby the apparatus may be readily cleaned whenever necessary; and to provide apparatus so constructed as to reduce the fire hazard to a minimum. We attain these and other objects of our invention by the apparatus illustrated in the accompanying drawings, in which—

Figure 1 is a side elevation of our invention;

Fig. 2 is a vertical section through the approximate central portion of the apparatus;

Fig. 3 is a horizontal section on line 3—3 of Fig. 2;

Fig. 4 is a horizontal section on line 4—4 of Fig. 2; and

Fig. 5 is a detail enlarged sectional view on line 5—5 of Fig. 3.

Like characters of reference designate like 35 elements in each of the several views.

Referring to the accompanying drawings, we provide a cleaning tank T in which the fabrics to be cleaned are placed and with which a clean solvent pipe 19 communicates, 40 said pipe 19 also communicating with the upper portion of the small caustic removing tank 24, this tank being arranged in the main or large tank C which holds the clarifying solution. The receiving tank C consists of 45 the main tank 6 having the tapered bottom portion 7 which opens into the top of small tank 1, which latter tank is provided with outlet pipe and valve 2. Opening out of the bottom of fabric cleaning tank T is a pipe

50 20 which communicates with the pump P which pumps the solution which has been used through pipe 21 and discharges it through the four-way nozzle or agitator 3 which is provided with perforations 4 and 55 which opens into the bottom portion of bottom tank 1, where the fluid is agitated by

contact with a plurality of baffle plates 5 radiating from the sides of this tank and disposed vertically as shown in Fig. 2. The annular extension 8 of the tapering wall 7 which projects into the upper portion of tank 1 also functions as a baffle member to increase the agitation of the solution before it passes upward through opening 9 into the upper main tank 6.

We provide a conical dome 10 in tank 6, this dome being provided with a series of apertures 12 arranged near its base; and also being provided with a vertical air vent 13 opening out of its apex and extending to the top of tank 6 and through cover 36, as shown in Fig. 2. An annular space 11 is provided between the bottom edge of dome 10 and the vertical wall of tank 6. The filtering tank 14 is provided with a filtering element 15 extending horizontally across its upper portion just below the point where pipe 19 opens into this tank. This filtering element consists of a plurality of wire mesh members 16 and cloth and cotton members 17, alternately arranged. Filtering element 15 is positioned immediately below opening 18 in which the end of pipe 19 is mounted. Pipe 19 is provided with a suitable sight glass 41. Similarly, pipe 20 is provided with a suitable sight glass 42. Pipe 20 is also provided with a hand-operated valve V. Opening into pipe 20 is a vertical filling pipe 43 having a valve 44 arranged in it, this pipe 43 terminating in a suitable funnel 45. The main tank 6 is also provided with a sight glass 35, and in addition with a glass gauge 38 projecting above the tank as shown in Figs. 1 and 2.

Mounted on the smaller tank wall 24, as shown in Fig. 2 is a downwardly-slanting baffle plate 26 which extends nearly, but not quite to the opposite wall of the tank, while mounted on the opposite walls are spaced baffle plates 25 slanting upwardly in parallel relation to baffle 26 and extending nearly but not quite to wall 24. We provide faucets 27 opening just above the respective baffle plates 25 and the bottom inclined wall of tank 24.

Arranged in tank 6 as shown in Fig. 2 we provide a pipe 28, terminating in a funnel 29, the top of which is even with the surface of the liquid contents of tank 6. Pipe 28 has a slanting extension portion 30 which terminates in the nozzle 31 which opens into the bottom of tank 24. We also provide a

horizontal pipe 34 extending from the two-way valve 32 in pipe 28 through the wall 33 of tank 14. The two-way valve 32 is controlled by the valve handle 33 as shown 5 in Fig. 3.

The tank is provided with a cover made in two sections, the larger section 36 of which covers the main tank 6, while the smaller section 37 covers the small tank 14 10 and its extension 24, as shown in Fig. 2.

Opening into the lower portion of tank 6 we provide an annular steam pipe 39 having spaced openings 40. The pipe 39 is in communication with pipe 46 which is 15 connected with some suitable source of supply of steam which is used to clean the bottom of the tank and heat the fluid.

In operating our invention, the garments or fabrics to be cleaned are placed in the 20 cleaning tank T where they are washed in gasoline and soaked for a time. Then the outlet valve V is opened and the dirty solution is pumped by means of pump P through pipes 20 and 21 and nozzle 3 into the bottom 25 of small tank 1. The settling solution is poured into funnel 45 and through pipe 43 into pipe 20, the contents of which are pumped with some force through pipes 21 and nozzle 3 into tank 1, thus mixing the 30 solvent, the mixing process being further aided by the plurality of radial baffle plates 5 and the annular baffle extension 8. The solvent S passes upward through opening 9 and spreads out over the conical bottom 35 wall 7 of main tank 6, also encountering the air dome 10, as indicated by the arrows in Fig. 2 of the drawings, all the air that may be in the solvent being permitted to escape through the air vent 13 at the apex 40 of dome 10. The solution flows through funnel 29, pipe 28, extension pipe 30 and nozzle 31 into tank 24 where it flows through water and around the series of baffle plates 25, 26 and 25, and upward through filtering 45 element 15 to pipe 19 through which it returns to the cleaning tank T in clarified condition ready for use again in cleaning the clothes or fabrics that are in this tank for the purpose of being cleaned.

50 The solid top 36 extending from one wall of the large tank over to the wall 14 of the smaller tank, and the top 37 of the smaller tank provide an efficient cover releasably attached as shown and reduces fire hazard.

55 If, for any reason, the filter 15 becomes clogged and will not allow the solvent to pass through into pipe 19 and to the cleaning tank T, the solvent will rise in the sight glass 38, thus warning the operator.

60 The openings 40 in the annular pipe 39 point downward so that steam admitted through pipe 39 will greatly facilitate the cleaning process, washing down any foreign substance which may have collected. The 65 various sight glasses shown in the drawings

are for the obvious purpose of allowing the operator to see the height and condition of the solvent.

The two-way valve 32, shown in detail in Figs. 5 and 3, affords the operator control 70 of the solvent, as he may direct it either through pipe 34 into the small tank directly under the filter 15 or may divert it through pipe 30 and nozzle 31 to the bottom of tank 24 letting the operator use the clear water 75 wash which takes place in that part of the smaller tank indicated as 24 in Fig. 2 of the drawings. This section of the small tank is filled with clear water. The solvent 80 after being cleaned as heretofore described, rises to the top of the large tank 6, flows through the pipe 28 and extension 30 to the bottom of the small tank 24 and is sprayed into the bottom compartment through the nozzle 31. Being lighter than water it flows upward past the several baffle plates until 85 it reaches the top of tank section 34 where the slanting wall 23 permits it to spread out before it flows through the filter 15 and back thereafter into the cleaning tank. By these 90 several steps we not only produce a cleaner solvent but have eliminated the possible chance of any free caustic remaining in the solvent. The faucets 27 permit of convenient 95 cleaning of the tank at any time such cleaning is needed.

The process described makes it possible to save a large percentage of the cleaning solvent. It also makes it possible to clean 100 rough and fine fabrics simultaneously with satisfactory results in both cases.

What we claim is:

1. In an apparatus for clarifying the solvent used in cleaning fabrics, the combination of a cleaning tank in which the fabrics are placed, a solution tank to which a solution for clarifying solvent is supplied, a conduit leading from the cleaning tank to the solution tank, means for forcing the solvent from the cleaning tank into and through the solution tank, a second tank into which the solution tank discharges the mixture, filtering means arranged in the upper portion of said tank last named, and a conduit arranged to conduct the clean solvent after it has passed through the filtering means back to the cleaning tank in which the fabrics are placed for cleaning.

2. An apparatus for clarifying the solvent used in cleaning fabrics, the combination of a solution tank, a cleaning tank in which the clothes are placed for cleaning, a conduit from said cleaning tank to the solution tank, means for pumping the solution through said conduit, means for admitting a settling solution into said conduit, means in the solution tank for agitating the solution, means for the escape of air from the solution, a filtering tank arranged within the main solution tank, a conduit leading 130

- from the upper portion of the solution tank to the bottom of the filtering tank, a series of baffle plates arranged in the filtering tank near its lower portion, a filter in the upper 5 portion of said filtering tank, and a conduit opening into the filtering tank at a point above the filter and extending to an opening into the cleaning tank in which the clothes or fabrics are placed for cleaning.
- 10 3. In combination with the apparatus described in claim 2, a conduit opening into the filtering tank at a point below the filter and in proximity thereto, said conduit opening out of the first-named conduit leading 15 from the upper portion of the solution tank to the bottom of the filtering tank, and a two-way valve controlling the flow of fluid through the respective points of discharge
- of said conduits, said two-way valve being operable by a handle arranged outside the 20 main tank, substantially as shown.
4. In combination with the apparatus disclosed in claim 2, a cover made in two sections, one of the sections covering the solution tank and the other section covering the 25 filtering tank, a dome arranged in the solution tank and having its periphery in proximity to but spaced from the wall of said tank, said dome terminating at its apex in an air vent, said air vent extending to and 30 discharging through the cover to the solution tank, the aforesaid dome having spaced apertures for the escape of the solvent.

RALPH HOLLAND.
JOHN A. WIRT.
